[57] CLAIM

The ornamental design for an animal leash, as shown and described.

DESCRIPTION

FIG. 1 is a top plan view of an animal leash showing my new design;

FIG. 2 is a bottom plan view thereof;

FIG. 3 is a front elevational view thereof;

FIG. 4 is a rear elevational view thereof; and,

FIG. 5 is an elevational view taken from one end thereof; and

FIG. 6 is an elevational view taken from the end opposite that shown in FIG. 5.

The leash has been broken away in FIGS. 1 through 4 to indicate indeterminate length.
